UNITED STATES PATENT OFFICE.

THEODOR E. SPRINGMANN, OF CHARLOTTENBURG, NEAR BERLIN, GERMANY.

PROCESS FOR OBTAINING NITRIC OXIDE.

Application filed November 1, 1922. Serial No. 598,434.

To all whom it may concern:

Be it known that I, THEODOR E. SPRINGMANN, residing at 91, Kantstrasse, Charlottenburg, near Berlin, Germany, have invented certain new and useful Improvements in Processes for Obtaining Nitric Oxide, of which the following is a specification.

This invention relates to a process for obtaining nitric oxide by heating fuel gas and air to a temperature high enough to obtain, by burning the preheated fuel gas and air, a temperature at which nitric oxide is formed, and then suddenly cooling the gas of combustion containing nitric oxide on water-cooled surfaces, such as for example, the walls or tubes of a steam boiler.

In known processes of this kind air is heated by electric discharges to the high temperature at which nitric oxide is formed, and the heated fluid is then suddenly cooled on water-cooled surfaces. The heat absorbed from the gases can be used for producing steam. A drawback of these processes is that the heating of the gases by electricity is very expensive.

The object of this invention is to remove this drawback and this is accomplished by producing the high temperature required for the combustion of oxygen and nitrogen in a gas combustion chamber of steam boilers, by feeding the gas burner in the said combustion chamber with fuel gas and air which has been preheated by any devices for heating gases such as for example a regenerator or recuperator.

The speed of circulation of the water in the steam boiler may be increased if necessary by artificial means such as a rotary pump in order to prevent the walls or tubes of the boiler being burnt through by the high temperature of combustion required for the process, this temperature being much higher than that in ordinary furnaces.

In order to prevent the said burning through of the walls or tubes of the boiler as a result of insufficient circulation of the water due to any causes whatever, the high temperature of combustion produced in the boiler furnace is preferably made dependent on the said circulation. This can be effect-

ed for example by throttling the preheated gas and air conducted into the furnace, or by conducting cold fuel gas into the furnace. Should it not be possible to maintain the circulation of the water during the working of the plant, the boiler may be kept in operation solely by means of gas and air which has not been preheated.

In contradistinction from other known processes for obtaining nitric oxide, the high temperature required for the combustion of nitrogen according to the new process is produced in a very economical manner, because only very little of the heat of the fuel is lost in the process of obtaining the high temperature necessary to obtain nitric oxide, while in producing the necessary heat by electricity only a small fraction of the heat of the fuel is utilized. Another advantage of the new process is that, in addition to obtaining nitric oxide, commercial high pressure steam is obtained very economically in a perfectly reliable boiler plant. A much smaller heating surface than in ordinary boilers is required to produce the same quantity of steam on account of the rate of evaporation being increased to a large extent by the very high temperature and the great speed of flow of water and combustion gas.

The invention is illustrated in the accompanied drawing in which—

Fig. 1 is a diagrammatic horizontal section through the plant, and shows the gas heating devices in the form of regenerators and a boiler with vertical water tubes.

Fig. 2 an end elevation of a boiler equipped with an artificial means for increasing circulation, this means consisting of a rotary pump.

Referring to the drawing, Fig. 1, 1 and 2 are heating devices for heating the fuel gases in the shape of regenerators, 3 and 4 are similar devices for heating the air of combustion, 5 and 6 are flues or chimneys for the exhaust gases which pass out of the regenerators, while they are being heated. 7, 9, 11, 13 are valves for controlling and stopping the flow of air and 8, 10, 12 and 14 are similar valves for controlling and stopping the flow of fuel gas into the

regenerator. The gas enters a distributing pipe at 15 and the air enters a distributing pipe at 16.

17 and 18 are valves for stopping the flow of gas from the regenerators into a pipe leading to a burner 21 in the furnace of the boiler and 19, 20 are similar valves for stopping the flow of air from the regenerators 3 and 4 into a pipe leading to the said burner 21.

22 are the water tubes of a tube boiler and 23 is a flue for conducting the fire gases from the boiler furnace. 24, 25, 26, 27 are valves for stopping the flow of combustion gases of the regenerators from the regenerators into the chimneys and 28, 29 are auxiliary valves for controlling the flow of air and gas through a by-path to the burner so as to enable gas and air which is not pre-heated in the regenerators to be supplied to the burner 21.

Gas and air may be sent alternately through pairs of heat exchangers in the following manner: In the first period of working the air valves 7 and 11, the gas valves 8 and 12, and the chimney valves 24 and 26 are opened, while the valves 17 and 19 leading to the burner are closed. Fuel gas and air will then burn in the regenerators 1 and 3, the gases of combustion escaping through the chimney valves 24 and 26 into the chimneys 5 and 6 or flues. The air and gas burnt in the regenerators 1 and 3 will produce heat and raise the temperature to the desired point.

At the same time the gas valve 10 and the air valve 13 and also the valves 18 and 20 are opened, while the chimney valves 25 and 27, the gas valve 14 and the air valve 9 are closed. Hence gas will flow through the regenerator 2 and air through the regenerator 4 which will impart the heat generated in them during the previous heating period to the gas and air. The gas and air are brought to a high temperature and pass through the valves 18, 20 to the burner 21 in the furnace of the steam boiler. The combustion of the preheated gas and air at the burner gives rise to temperatures that are so high that nitric oxide is formed. The sudden cooling of the gases containing nitric oxide by the pipes 22 of the steam boiler prevents the formed nitric oxides from decomposing into their component parts. The cooled combustion gases containing nitric oxide pass through the combustion gas flue 23 to the apparatus in which the nitric oxides are washed out.

Regenerators 2 and 4 preheat fuel gas and air and so are cooled in the same measure as the regenerators 1 and 3 are being heated at the same time, until the various valves are operated to start the second or next period in the process.

Second period: The air valves 9 and 13, 65 the gas valves 10 and 14, and also the chimney valves 25 and 27 are opened, while the valves 18 and 20 are closed. Consequently gas and air will be burnt in the regenerators 2 and 4, and the burnt gases pass out through 70 the chimney valves 25 and 27 into the chimneys 5 and 6. The regenerators 2 and 4, whose temperature was lowered during the first period, are now heated up to the temperature required for subsequently preheating the air and gas to be passed through them.

At the same time the air valve 7, gas valve 12 and chimney valves 24, 26 are closed, while the valves 17 and 19 are opened. 80 Consequently gas will flow through the regenerator 1 and air through the regenerator 3 so that these regenerators will now impart the heat which they have received during the first period to the gas and air passing 85 through them. The gas and air passes through the valves 17 and 19 to the burner 21 in the boiler furnace where they are burnt.

In the further working of the process the 90 different periods alternate in the manner described for the two periods.

Should it be necessary to lower the temperature of combustion in the boiler, air and gas which have not been preheated may be 95 introduced into the boiler furnace through by-passes controlled by the valves 28 and 29.

In some cases the temperature of combustion required for the formation of nitric oxide may be obtained by preheating the air 100 or the fuel gas only.

In Fig. 2 the manner in which the speed of circulation of the water in the boiler-tubes can be increased by artificial means is shown. A pipe *a* connects the top boiler 105 *b* with the bottom boiler *c*, and a rotary pump *d* is provided in the pipe, which pump may be driven by an electromotor or similar device.

The gas heating device for preheating the 110 gases may be of any preferred type. Thus, instead of using a regenerator in which a firebrick lining alternately receives and yields up heat from, or to a medium or fluid which is in direct contact with the said 115 lining, a recuperator may be employed through which the two mediums (the one which receives heat and the other which imparts heat) flow continuously in separate channels separated by a dividing wall which 120 conducts heat from the one gas to the other.

Many variations of the plant used for carrying out this process are possible without departing from the scope of the invention.

I claim:—

Process for obtaining nitric oxide, comprising preheating both fuel gas and air to

a temperature high enough to obtain by burning the gases a temperature at which nitric oxide is formed and keeping the gases entirely separate from each other during the preheating, burning the gases, and cooling the gas of combustion immediately after it is formed by bringing it into direct contact with the outer surface of a steam boiler so

as to prevent dissociation of the nitric oxide which it contains.

10

In testimony whereof I have affixed my signature in presence of two witnesses.

THEO. E. SPRINGMANN.
